UNITED STATES PATENT OFFICE.

ERNEST A. BOEHM, OF ST. LOUIS, MISSOURI.

COUPLER FOR KEYBOARDS OF PIANOS.

SPECIFICATION forming part of Letters Patent No. 553,829, dated February 4, 1896.

Application filed September 6, 1895. Serial No. 561,680. (No model.)

To all whom it may concern:

Be it known that I, ERNEST A. BOEHM, a citizen of the United States, residing at St. Louis, in the State of Missouri, have invented certain new and useful Improvements in Couplers for the Keyboards of Pianos, of which the following is a full, clear, and exact description, reference being had to the accompanying drawings, forming a part hereof.

10 My invention has relation to improvements in couplers for the keyboards of pianofortes; and it consists in the novel arrangement and combination of parts more fully set forth in the specification and pointed out in the claims.

15 In the drawings, Figure 1 is a plan view of my complete invention. Fig. 2 is an end view thereof. Fig. 3 is a sectional detail showing one of the pegs controlled by one end of the coupler. Fig. 4 is a perspective view 20 of the coupler detached; and Fig. 5 is a view similar to that shown in Fig. 2, showing the coupler completely "off" or disengaged.

The object of my invention is to construct 25 a coupler for piano-keyboards whereby, when a certain key of the board is struck or depressed by the finger of the operator, the corresponding note of the next succeeding octave may be made to respond simultaneously with the note struck.

30 The present device may be attached to the ordinary upright piano of any of the standard makes, and can automatically be disengaged from or be brought into engagement with the keyboard at the will of the operator. In detail the invention may be described as follows:

35 Referring to the drawings, 1 represents a long narrow board covered preferably with cloth on the upper surface and on which the series of couplers are pivotally mounted.

40 Each coupler is composed of a medial member 2, a short terminal arm 3, substantially at right angles to the member 2, a deflected portion 4, also substantially at right angles to the member 2, but disposed perpendicularly 45 to the arm 3, and an outwardly terminal extended arm 5, forming a continuation of the deflected portion 4 and parallel substantially to the arm 3 and extending in the same direction therewith. The member 2 forms the 50 pivot about which the arms 3 and 5 oscillate, the several members 2 being each pivotally secured to the board 1 by the free end of a me-

tallic strap or clip 7, riveted at one end to the board at either end of the member 2 and adjacent respectively to the arm 3 and the deflected portion 4, each clip having interposed between it and the member 2 a piece of cloth 8. Secured by suitable blocks 9 and parallel to the longitudinal edge of the board 1 is a strip 10, provided with a series of openings 60 11, each adapted to loosely receive a vertically-operating peg 12, having an upper terminal felt-covered head 13 held normally a slight distance above the upper surface of said strip.

65 The construction of the coupler is such that the several medial members 2 can be arranged side by side in parallel series diagonally across the board 1, as best seen in Fig. 1. The board 1 is pivoted along its front longitudinal edge at either end thereof by a hinge 14, secured to the front edge of a standard 15, carried at either end of the piano-frame at any convenient point thereof. The medial portion of the rear edge of the board 1 is pivotally connected by a depending lug 16 and a rod 17 to one of the pedals 18, the position of which, as shown in full lines in Fig. 2, is its depressed position—that is, as held down by the foot of the operator.

70 The construction of the keyboard and the action of the risers or abstracts operated upon the depression of any key is not here entered into, that being a feature which is well known and old and forming in no way the subject- 75 matter of this application. Suffice it to say, however, that when any key—for example, "X"—is struck or depressed, the rear portion thereof raises the abstract or riser 19 controlled by it. Now each abstract under my 80 present invention is provided with a right-angled projecting arm 20, the free end of which carries a vertically-adjustable screw-threaded rod 21, whose lower end is provided with a felt-covered head 22 and superposed 85 directly over the free end of the extended arm 5 of the coupler. At the same time the arm 3 of the coupler is located immediately over the head 13 of the peg 12 of the key removed one octave distant, it being understood that 90 the length of the member 2 of each coupler is such that the arms 3 and 5 co-operate with abstracts removed just one octave apart.

95 When the board 1 and strip 10 are depressed,

or when the coupler is "on," as shown in full lines in Fig. 2, the head 13 of the peg 12 is held at a suitable distance above the upper surface of the strip 10 by the rear end of the key operating the peg. The head 13 thus slightly elevated tilts the arm 3 of the coupler out of contact with the board 1 to which the coupler is pivoted, tilting it at its free end an amount equal to the distance that the head 13 of the peg has been raised above the surface of the strip 10 by the rear of said key. Under these circumstances, too, the free end of the arm 5 is in contact with the felt-covered head 22 of the rod 21. As seen from the drawings, the end of the member 2 which forms the pivot for the member 3 is located a slight distance from the revolving longitudinal edge of the board 1, so that the base of the arm 3 is adapted to rest and be supported by the board when the coupler is allowed to tilt or drop to its lowest position relatively to the upper surface of the board. Now when it is not desired to use the coupler the operator removes his foot from the pedal 18, the latter assuming its normal position through the action of the free end of the resilient flexed spring 25 secured at one end to the inner surface of one or both of the standards 15, which spring not only raises the pedal to its normal position, but tilts the coupler-carrying board 1 to its highest position, as shown in Fig. 5. As the board is thus being swung upward about its pivotal edge, it is apparent that in this motion the pivotal point or end of the swinging member 3 is raised; but as the pivotal end of the said member 3 is thus raised the effect is to depress the free end of the said member or arm 3—that is to say, the effect is to bring said arm more nearly to the horizontal while yet supported by the peg 12. (See dotted position of the parts in Fig. 2.) While the free end of the arm 3 is thus being relatively depressed or tilted, the free end of the arm 5, which had heretofore (that is, during the depressed position of the board 1) been in contact with the base of the rod 21, will drop away from said rod, but a greater distance than the free end of the arm 3 has dropped, owing to the fact that it is longer and the further fact that its pivotal point is in fact the juncture of the deflected portion 4 with the member 2. The coupler-arms 3 and 5, therefore, will drop, as it were, until arrested by reason of the arm 3 being supported and arrested by the upper surface of the board 1. This arrest of the coupler-arms happens when the strip 10 has just come in contact with the base of the head 13 of the peg 12. A further upward sweep of the board 1, therefore, will raise the base of the peg 12 away from the rear end of the key which had previously supported it and at the same time raise the free end of the arm 5 a second time into contact with the base of the rod 21, the free end of the arm 3 being at all times of course supported by the head 13 of the peg 12; but as the peg itself is now out of contact

or reach of any action of the key the possibility of the peg 12 being raised to elevate the arm 3 disappears, and the coupler under these circumstances therefore will be disengaged. (See Fig. 5.)

To re-engage the coupler, the board 1 is again depressed, when the first effect of such depression will be to remove the free end of the arm 5 out of contact with the rod 21 and lower the peg 12 sufficiently to bring the same to rest on the rear of the key operating it. A further depression of the board will cause the head 13 of the supporting-peg 12 to tilt the arm 3 upwardly and at the same time to tilt the free end of the arm 5 upward till it comes again in contact with the base of the rod 21, when the parts will again be in their coupled position—that is to say, the coupler will be "on"—as represented in full lines in Fig. 2.

It is apparent that when the coupler is "on" if the operator, for example, strikes the key "X" the rear end of said key will raise the abstract 19, as usual, and produce the sound or note corresponding to that key. At the same time the rear end of the same key will raise the peg 12, its head 13 raising the free end of the arm 3, thus tilting the coupler upward about its pivotal member 2 and causing the free end of the extended arm 5 thereof to raise the felt-covered head of the rod 21, removed just one octave to the right, which rod 21 in turn raises the abstract 19' carrying the same and removed one octave from the abstract 19, and thus sounding the note corresponding to the key "X'" represented by said abstract 19'.

The present device is applicable not only to pianos, but to organs and similar instruments.

Having described my invention, what I claim is—

1. In a piano, suitable couplers having medial portions adapted to be arranged and pivoted in parallel series, each medial portion thus pivoted having arms at either end deflected in the same direction from their common medial portion adapted to co-operate with the abstracts of keys removed one octave apart, substantially as set forth.

2. In a piano, a coupler having a medial portion, a terminal arm substantially at right angles to the medial portion, a deflected portion at the opposite end of the medial portion also substantially at right angles to the medial portion but disposed perpendicularly to the terminal arm, and an extended arm forming a continuation of the deflected portion and parallel substantially to the terminal arm, substantially as set forth.

3. In a piano, a suitable board, a series of movable pegs mounted in the line of the keys of the piano and adapted to be controlled each by the depression of its corresponding key, a suitable coupler operated by the action of each key, and suitable connections between the coupler and the abstract of the key removed one octave, for simultaneously con-

trolling said abstract and sounding the note corresponding thereto, substantially as set forth.

4. In a piano, a suitable pivoted board, a pivotal connection between its free edge and the pedal-lever, a series of couplers having terminal arms deflected substantially parallel to one another carried by the board and adapted to co-operate with the keys when the board is in its depressed position, and suitable means for disengaging the couplers and board from the keys, substantially as set forth.

5. In a piano, a suitable spring-actuated longitudinally-pivoted board, means for controlling said board from the pedal-lever, a series of couplers having medial portions pivoted to the board diagonally across the same in successive series, a terminal arm for each coupler, a series of vertically-operating pegs actuated by the rear of the keys and adapted to control the short or terminal arm of the coupler, an upwardly-deflected portion also substantially at right angles to the medial

member but perpendicular to the terminal arm, an outwardly-extending terminal arm 25 forming a continuation of the deflected portion and substantially parallel to the terminal arm, a series of abstracts or risers co-operating with the several keys, a vertically-adjustable rod carried by each abstract and 30 adapted to co-operate with the long terminal arm forming a continuation of each deflected portion of the couplers, the terminal arms of the several couplers co-operating simultaneously with keys removed one octave, and 35 suitable spring-clips at either end of the medial portions of the couplers forming the pivotal connections between the said couplers and the board carrying the same, substantially as set forth. 40

In testimony whereof I affix my signature in presence of two witnesses.
